3 Sheets-Sheet 3

in a second shoulder 28 extending to the upper edge of an involute face 29 which delineates the wall of a centrifugal pump. A discharge pipe 30^a communicates with the interior of the lower section of base 22 at the widest point of the involute.

The stator member 30 of mill 10 consists of an integrally formed lower cylindrical portion 32 and an upwardly extending coaxial upper cylindrical portion 33, of lesser diameter. The intermediate outer surface of the stator lower portion 32 is threaded as at 34 and engages the threaded face of base wall 24 thereby to effect interconnection between base 22 and stator 30 and permit relative longitudinal adjustment therebetween. The lower border of stator portion 32 is inwardly offset and provided with a peripheral groove in which is nested a gasket 36 for effecting a liquid-tight seal between the confronting faces of stator 30 and base wall 27.

In order to lock stator 30 in a preselected vertical position, a ring 37 is located and secured to the upper face of base wall 24 and secured thereto by suitable screws, the outer periphery of ring 37 being provided with regularly spaced notches 38. A latch element 39 is disposed on the upper face of stator 32 and includes a radially extending arm 40 provided with a rear and an intermediate aperture and terminating at its outer end in a narrow depending leg 41 separably engaging a notch 38. Latch 39 is releasably locked in position by means of a headed bolt 42 having an axial shank registering with the intermediate aperture of latch 39, and a lower threaded shank engaging a corresponding tapped bore in stator 32. The rear aperture in latch 39 is slidably engaged by a pin 43 affixed to stator 32. Also releasably locking stator 30 in a preselected position and inhibiting the loosening thereof and leakage therefrom is an adjustable nylon set screw 44 engaging a corresponding tapped bore formed in the base wall 24 which extends to the threaded section thereof.

Formed in the top face of the upper stator portion 33 is an outer lower peripheral shoulder 46 separated from an inner raised shoulder 47 by a vertical cylindrical wall, shoulder 47 being in turn separated from the upper edge of stator portion 33 by a vertical cylindrical wall to define, with the shoulder 47, a recess which is engaged by a circular gasket 48 formed of any suitable resilient material.

A coupling member 49 includes a lower peripheral flange 50 terminating in a depending lip 51 which abuts shoulder 46 and is affixed thereto by bolts 52 registering with openings in flange 50 and engaging corresponding tapped bores in stator 33. A conical wall 53 projects upwardly from the inner edge of flange 50 and terminates in an upwardly directed externally threaded tubular member 54. Coupling member 49 may engage the internally threaded neck of a funnel-shaped hopper 12 or any suitable pipe or fluid feed member.

The inner face of stator 30 is divided into a first upper or main section 56, an intermediate section 57 and a bottom section 58. Upper section 56 occupies most of the inner surface of the stator and is of conical configuration having a relatively small vertex angle substantially of the order illustrated. Formed in section 56 are a plurality of regularly circumferentially spaced, longitudinally extending grooves 59 of arcuate cross-section which are separated by intervening teeth or ribs 60. It should be noted that the depth of grooves 59 decreases from the top to the bottom of stator 30, as does the height of the intervening teeth 60, the widths of which increase.

Intermediate stator surface section 57 is of horizontal annular configuration, the inner edge of which extends from the lower edge of surface section 56. Furthermore, the lower stator surface section 58 is of conical configuration having a relatively high vertex angle as compared to that of the upper stator surface section 56. Regularly circumferentially spaced, longitudinally and radially extending slots 63 are formed in stator sections 57 and 58 and have arcuate bases 64. Slots 63 delineate intervening teeth or ribs 65, the outer faces of which define stator surface sections 57 and 58.

The mill rotor includes an assembly of an upper section 66, an intermediate core section 67 and a lower section 68, the assembly being suitably mounted on a vertical shaft 69. Shaft 69 is provided with a lower portion which passes coaxially through column 18 registering with bearing members 21, and is connected by way of a coupling 70 to the drive shaft of an electric motor 71 which is vertically supported on mount plate 14. Shaft 69 is locked in position by means of an integrally formed collar 72 having a conical underface engaging upper bearing 21 and a nut 73 which engages a threaded section of shaft 69 and abuts the underface of lower bearing 21, whereby said shaft 69 is locked against vertical movement. A suitable packing member 74 nests in collar 26 and engages shaft 69 to effect a liquid-tight seal.

Upper section 66 of the rotor includes a top portion 76 of frusto-conical configuration having an outer peripheral face of substantially the same vertex angle and of slightly less diameter than the upper portion of the internal surface section 56 of the stator. Located on the top face of rotor section 66 are a plurality of circumferentially spaced, radially extending vanes 77 which define an impeller for driving the liquid or fluid fed into the mill to the outer perimeter where it flows through the comminuting zone. Vanes 77 project from a centrally located collar 78 provided with a tapped axial bore which is separated from a coaxial bore of similar diameter formed in the bottom of rotor portion 76 by an intermediate bore 79 of reduced cross-section.

Depending from the lower peripheral edge of rotor portion 76 and formed integral therewith is a plurality of regularly circumferentially spaced, elongated vibrating elements or tines 80, each of which is of substantially trapezoidal transverse cross-section, with an outwardly directed base 81. The outer face of each tine delineates a conical surface which confronts and is closely spaced from the lower portion of the stator surface 56, and the adjacent sides of tines 80 converge outwardly to the spaces between the tines. Tines 80 increase in cross-section from the tops to the bottoms thereof, and should resonate at a fundamental frequency in the sonic range and advantageously between about twenty and thirty kilocycles per second and should preferably be capable of producing strong harmonics.

Formed in the peripheral face of rotor portion 76 is a plurality of circumferentially spaced longitudinally extending grooves 82 of arcuate cross-section, which grooves communicate and are colinear with the spaces between tines 80. The grooves 82 delineate intervening ribs or teeth 83 which advantageously differ in number from the teeth 60, preferably being one more or less.

Underlying rotor section 76 and surrounded by the tines 80 is the frusto-conical core section 67 secured to the underface of the rotor section 76 by connecting screws 86 engaging corresponding aligned tapped bores in rotor sections 67 and 76. The outer face of the rotor section 67 is spaced inwardly from the inner faces of the tines 80, and has formed therein circumferentially spaced longitudinally extending grooves 87 which are in radial alignment with the axes of the adjacent tines 80. An axially extending bore 88 is formed in rotor section 67 which is coaxial with and of greater diameter than the axial bore formed in the rotor section 76.

Rotor section 68 includes a lower annular member 89 having an inner conical face surrounding and spaced from the peripheral surface of collar 26 and a flat bottom face parallel to and closely spaced from the upper face of base wall 23. The inner upper edge of the annular member 89 is bridged by a web 91 having a raised portion 92 which registers with a corresponding recess formed in the underface of rotor portion 67. Rotor portions 67 and 68 are interconnected by a plurality of screws 94 engaging aligned tapped bores formed therein. The peripheral face of the annular member 89 is spaced from the involute surface 29 and has a circumferential channel

shaped groove 96 formed therein. Located in the groove 96 are a plurality of spaced radially extending impeller-defining vanes 97.

The upper face of annular member 89 includes an outer conical face 98 which is parallel to and closely confronts the stator surface section 58 and an inner upper annular face 99 which is parallel to and closely confronts the stator surface section 57. Radially extending slots 100 are formed in rotor faces 98 and 99, and are regularly peripherally spaced therealong, the number of slots 100 being different than the number of slots 65, for example by one, and being many times greater than the number of slots 82.

The rotor is carried by shaft 69, as noted above, the lower axial bore formed in the rotor upper section 66 registering with the upper section 101 of shaft 69. The underface of rotor portion 76 rests on the upper face 102 of the rotor section 67. The axial bores in the rotor sections 67 and 68 engage the shaft section 103 and a key 104 registers with aligned keyways formed in the shaft section 103 and the confronting face of the rotor bore. The rotor is locked against longitudinal movement in shaft 66 by a screw 106 extending through bore 79 and engaging a tapped bore in the shaft stub end 101. Feed screw 107, coaxial with the rotor and coupling member 54, is provided with a bottom threaded shank engaging the tapped coaxial bore in the upper end of shaft 69.

In the operation of the apparatus described above, the rotor is driven by motor 71 at a high speed, for example 3600 r.p.m., and the mixture of fluid and solid particulate material to be homogenized is introduced into the hopper and drops or is screw-fed to the vanes 77. The mixture is centrifugally driven to the peripheral zone and into the space between the confronting faces of the rotor portion 76 and upper stator face 56. There the mixture is subjected to an intensive shearing action and the solid phase reduced in particle size by shear impact and interparticle attrition. As the mixture reaches the zone delineated by the tines 80, it follows a highly tortuous and turbulent path about the tines 80 where the solid particles are highly reduced in size and by impact, shear and interparticle friction, which action is greatly enhanced by the intensive high frequency vibration of the tines 80. The presence of the vibrating tines 80, excited by the rotation of the rotor and the movement of the mixture, radically increases the efficiency and effectiveness of the present apparatus. The mechanism and mode of operation is not completely understood although several theories have been proposed. As the mixture leaves the zone of the tines 80, it passes through the zones delineated by the stator faces 57 and 58 and the rotor faces 98 and 99 where further reduction and dispersion is effected in the manner earlier set forth. The homogenized mixture is then sucked by the pump including the impeller 97 and discharged through the pipe 30a. As the material being processed is drawn downward to the region of tines 80, the latter impel the material inwardly toward the core 67 because of their inwardly converging faces, thereby reversing the flow of the material before it reaches stator faces 57, 58, whereat further reduction occurs.

As an example of a mill in accordance with the present invention, there are provided 27 tines 80 each having a length of about $1\frac{1}{4}$ ", a bottom outside width of $\frac{5}{16}$ ", a top outside width of $1\frac{5}{64}$ " and a depth of $\frac{3}{16}$ ". The rotor is formed of a type 316 stainless steel. During operation, the rotor was driven at 3600 r.p.m. and the measured frequency in the liquid at the downstream or discharge end was registered between about 6 and 60 kilocycles per second with a predominance in range of 20 to 30 kilocycles per second. In the absence of fluid, the magnitude of vibration was considerably less with a greater frequency scatter.

An asphalt emulsion processed with the apparatus under the above conditions, upon an examination under an

electron microscope, exhibited an average particle size of 1.1 microns with a range between 0.7 and 4.5 microns as compared with the same asphalt emulsion processed with a pressure type homogenizer which had an average particle size of 4.5 microns and a particle size range between 1.5 and 10.5 microns. It should be noted that the operating conditions of the apparatus may be altered by adjusting the spacing between the stator and rotor by releasing the latch 39 and turning stator 30 in base 22 as desired and then locking latch 39. By reason of screw 44 being formed of an organic thermoplastic material, it reforms its end face to effect a liquid-tight seal. It may be repeatedly reemployed, as, in case of wear, the contacting face of the screw 44 can be—in effect—renewed by a half turn to reestablish its normal sealing and compression effect.

While there has been described and illustrated a preferred embodiment of the present invention, it is apparent that numerous alterations, omissions and additions may be made without departing from the spirit thereof.

I claim:

1. An improved comminuting apparatus, comprising a stator member having an inner conical surface, and a rotor member coaxial with said stator member and including a core member having an outer conical surface and a plurality of circumferentially spaced longitudinally extending vibrating tines spaced from and around the surface of said core member, each of said tines having one end thereof fixed to said core member and the other end thereof free, said tines having inner faces lying on a conical surface directly and unimpededly confronting said core outer surface to delineate therewith an uninterrupted peripheral zone bounded by concurrently moving surfaces, outer faces lying on a conical surface confronting and spaced from said stator inner surface and said core member having formed in the peripheral face thereof longitudinal grooves substantially registering with said tines.
2. A comminuting apparatus in accordance with claim 1, wherein said tines have side faces converging inwardly toward said core grooves.
3. The comminuting apparatus of claim 1, wherein the inner conical surface of said stator member has circumferentially spaced longitudinally extending grooves formed therein.
4. The comminuting apparatus of claim 3, wherein said tines and said grooves formed in said inner conical surface of said stator member differ in number.
5. An improved comminuting apparatus comprising a base member including a bottom wall and an upstanding peripheral wall, a stator member having an inner conical surface, means securing said stator member to the peripheral wall of said base member, a rotor member coaxial with said stator member, said stator member being longitudinally adjustable relative to said rotor member, said rotor member including a core member having an outer conical surface and a plurality of circumferentially spaced longitudinally extending vibrating tines spaced from and around the surface of said core member, each of said tines having one end thereof connected to said core member and the other end thereof free, said tines having outer faces lying on a conical surface confronting and spaced from the inner surface of said stator and inner faces lying on a conical surface directly and unimpededly confronting said core outer surface to delineate therewith an uninterrupted peripheral zone bounded by concurrently moving surfaces, and means rotatably supporting said rotor member on said base member.
6. An improved comminuting apparatus, comprising a stator member having an inner conical surface, and a rotor member coaxial with said stator member and including a core member having an outer conical surface and a plurality of circumferentially spaced longitudinally extending vibrating tines spaced from and around the

surface of said core member, each of said tines having one end thereof connected to said core member and the other end thereof free, said tines having outer faces lying on a conical surface confronting and spaced from the inner surface of said stator and inner faces lying on a conical surface directly and unimpededly confronting said core outer surfaces to delineate therewith an uninterrupted peripheral zone bounded by concurrently moving surfaces, the inner surface of said stator being provided with a second surface of revolution of greater vertex angle than said conical surface and extending outwardly from the base of said conical surface and a third surface of revolution extending outwardly from said second surface of revolution and of smaller vertex angle relative thereto, said rotor being provided with sections below said core member which have outer surfaces corresponding to and confronting the second and third surfaces of revolution of said stator.

7. A comminuting apparatus in accordance with claim 6, wherein said stator second and third surfaces and the

confronting surfaces of said rotor have longitudinally extending grooves formed therein.
